COMBINED DISPLAY AND MERCHANDISING RACK FOR PACKAGED GOODS

Stephen Belejack, 716 Columbus Ave., Boston 20, Mass.

Filed Nov. 3, 1960, Ser. No. 62,726

Term of patent 14 years

(Cl. D80—9)

FIG. 1 is a front perspective view taken from the left side of a combined display and merchandising rack for packaged goods, showing my new design; and

FIG. 2 is a rear perspective view taken from the right side thereof, the shelves being omitted for convenience of illustration.

The dominant features of my design reside in the full line portions of the drawings.

I claim:

The ornamental design for a combined display and merchandising rack for packaged goods, as shown and described.
